METHOD AND MEANS FOR ACTIVATING CATHODES

Application filed December 6, 1930, Serial No. 500,600, and in Germany March 18, 1930.

This invention relates to methods and means for activating cathodes and more particularly to electron emitting cathodes for electron discharge devices.

5 The activation of electron emitting cathodes in discharge devices is easily accomplished at the present time with the aid of thermit reaction. The cathode of the evacuated vessel is heated and a potential applied 10 between the cathode and anode, a suitable resistance being inserted in the circuit to prevent any excessive increase of the anode current. A small amount of a thermit mixture such for example, as aluminum and barium 15 oxide is applied upon or in the anode. The anode is heated by means of a high frequency field to such a degree that the thermit reaction will be initiated. The temperatures necessary for the thermit reaction are rather 20 high so that the anode must be heated to such an extent that there is danger of its melting or losing its shape. There is danger also that due to the high heating employed portions of 25 the anode material may vaporize and deposit upon cooler parts of the device, such for example, as the grid insulation or the press whereby the insulation between the electrodes may be appreciably impaired and short circuits may result.

30 Such an intense heating of the anode would not of itself be necessary. It would only be necessary to heat the anode to a temperature which is just slightly above the ignition temperature of the thermit mixture. With eddy 35 current heating, however, it is not possible to prevent the heating of certain portions more than others. It is well known, for example, that in the heating of a metal sheet 40 that the edges become heated to a greater extent than the central portion of the sheet. Similarly it happens that certain portions of the anode are heated excessively while other portions remain comparatively cool. Those 45 parts of the anode at which the thermit mixture is located and which require the greatest amount of heat will be raised to the necessary ignition temperature at the last, while the portions situated away from that on 50 which the thermit mixture is located may al-

ready be heated to a considerably higher temperature.

According to the present invention the initiation of the thermit reaction is effected by 55 forming microscopic places of high temperature by means of so-called scintillation or ignition points. It is not then necessary for the initiation of a thermit reaction that the entire thermit mixture be brought to the ignition 60 temperature. It is sufficient that only a microscopically small part reach the critical temperature. The thermit reaction then automatically proceeds throughout the entire mass.

65 Electron bombardment may be used expediently for the production of such scintillation or ignition points. If the proper precautions are exercised so that the cathode has a definite electron emission before it is activated by the thermit method, the cathode 70 may be used to bombard the thermit mixture and to produce localized high temperatures at the scintillation or ignition points.

75 The procedure for producing and activating a discharge device will be explained in the following specification with reference to the accompanying drawings. In Fig. 1 there is shown a discharge device 1 which contains an incandescent cathode 2, a grid 3, and an anode 4. The cathode 2 preferably consists 80 of a core on which oxides, carbonates, hydrides, nitrites, separately or mixed, of alkaline earth metals, are applied. The grid 3 is connected with the cathode through a battery 85 5 and a protective resistance 6 so that it operates as an anode for the cathode. At this stage of the activation the following method of procedure is employed: The cathode is formed, i. e. the oxides are formed from the compounds of the earth alkaline metals, insofar as pure oxide is not already present on the cathode. Simultaneously a weak activation occurs as metallic ions of the alkaline earth metal are formed on the surface of the cathode by electrolysis or diffusion in islands, which represent or constitute the ignition centers. The electrons emitted from the cathode are drawn, under the influence of the applied grid voltage, to the grid and strike the 90 grid with great speed. This electron bom-

bardment heats the grid and completely de-gasses it.

The cathode so treated shows certain emission qualities. Inasmuch as the metallic emission centers constitute only a limited portion of the cathode surface, the emission is not as great as it would be if the cathode surface were completely covered with an alkaline earth metal.

10 The electron emitting surface of the cathode may be increased by additional evaporation of alkaline earth metal. Here begins the second part of the activation process. Fig. 2 shows symbolically the circuit employed for the second part of the process. The numerals 1, 2, 3 and 4 designate the corresponding parts shown in Fig. 1. The grid and cathode are connected by a battery 5 and a protective resistance 6 so that the grid has 15 a small positive potential with respect to the cathode. The cathode 2 is connected with the anode 4 through an anode battery 7, a stabilizing resistance 8 and a switch 9.

20 The electrons emitted from the cathode 2 are attracted to the highly positive anode through the influence of the slightly positively biased grid and the influence of the highly positive anode. The electrons not only come in contact with the anode material but also strike the surface of the thermit mixture which is so disposed that it can be struck by a large number of electrons.

25 The impinging electrons produce a strong heating of the thermit mixture at microscopically small places and this heating is of sufficient intensity to initiate the thermit reaction. During the thermit reaction metallic barium in the form of barium vapor entirely or partially ionized by electron impacts is released. The positive alkaline earth metal ions pass to the negative cathode, combine with electrons on the cathode to become neutral alkaline earth metal atoms or molecules and thereby cover the cathode with a layer of 30 alkaline earth metal. The vaporized barium which does not deposit upon the cathode deposits upon other electrodes and operates as a getter material. It is, of course, obvious that any other getter material such, for example, as magnesium may also be employed in addition to the alkaline earth metals not deposited upon the cathode. Precaution must be taken, however, that these auxiliary 35 getter materials do not deposit on the cathode and thereby seriously impair the electron emission properties of the cathode. The prime advantage of initiating the thermit reaction by the formation of scintillation or ignition points over the usual high frequency heating method resides in the fact that the temperature produced at the microscopically small points on the anode is approximately 200° lower than the temperature necessary for satisfactory high frequency heating, so 40 that the previously mentioned disadvantages

such as melting, distortion of the anode and the like, are overcome.

The initiation of the thermit reaction substantially increases the emission capacity of the cathode, for the cathode temperature is simultaneously increased by the ion bombardment. This action occurs in a very short time and a low voltage luminous arc is produced which may quickly lead to the destruction of the entire discharge device or at least to the destruction of the activated cathode. The space between the anode and the cathode constitutes a negative resistance so that the discharge current increases while the voltage at the discharge space decreases. It is possible to utilize this phenomena to indicate the beginning of the low voltage luminous arc.

45 Fig. 3 shows in combination a discharge device 1 comprising a cathode 2, a grid 3, an anode 4 and a grid battery 5, a protective resistance 6, an anode battery 7, a stabilizing resistance 8 and a switch 9. A voltage relay 10 is connected in parallel with the anode 4 and cathode 2 and functions to indicate that the thermit reaction has taken place and a low voltage arc discharge has formed.

50 Such indicating devices may seem to be superfluous inasmuch as the thermit reaction is indicated by a strong lighting in the discharge tube. However, as the devices usually have highly mirrored glass walls, the illumination in the discharge device cannot always be seen with certainty so that it is advisable that the presence of the illumination or the low voltage arc be indicated by some signaling device as described. It is possible, of course, to use the voltage relay 10 to operate the switch 9 so that the activation process is automatically interrupted at the proper moment. It may be advantageous under certain 55 conditions to allow the low voltage arc discharge to continue for one or two moments before the discharge current is disconnected. For this purpose the voltage relay 10 may be provided with a retarding device which 60 may give any desired retardation. The relay is preferably so constructed that the retardation period can be adjusted to any desired value.

65 The invention is applicable not only to discharge tubes having a grid but is equally applicable to discharge tubes having a plurality of grids or auxiliary electrodes.

What is claimed is:

1. In combination, an electron discharge device comprising a cathode, an anode adjacent said cathode, a thermit mixture including an alkaline earth metal compound upon said anode, means for heating said cathode, series means including a source of potential and a stabilizing resistance between said anode and said cathode, and indicating means in shunt with said series means.

2. In combination, an electron discharge device comprising a cathode, an anode ad-

adjacent said cathode, a thermit mixture of an alkaline earth metal compound upon said anode, means for heating said cathode, means for applying a potential between said anode and said cathode whereby said thermit mixture is ignited by electron bombardment, and means in shunt with said anode and cathode for indicating the voltage therebetween.

3. In combination, an electron discharge device comprising a cathode, an anode adjacent said cathode, and a thermit mixture including an alkaline earth metal compound upon said anode, means for heating said cathode, a series circuit including a source 10 of potential between said cathode and anode for causing ignition of said thermit mixture by electron bombardment, and means in shunt with said series circuit operable at a predetermined voltage between said anode 15 and cathode for opening said series circuit.

4. In combination, an electron discharge device comprising a cathode, an anode adjacent said cathode, a thermit mixture including an alkaline earth metal compound 20 upon said anode, means for heating said cathode, series means between said anode and cathode including a source of potential and a switch for causing ignition of said thermit mixture by electron bombardment, and means 25 in shunt with said series means for automatically opening said switch when the thermit reaction has occurred.

5. In combination, an electron discharge device comprising a cathode, an anode adjacent said cathode, a thermit mixture including an alkaline earth metal compound 30 upon said anode, means for heating said cathode, a series circuit between said anode and cathode including a source of potential, 35 a stabilizing resistance and a switch, whereby said thermit mixture is ignited by electron bombardment, and a relay in shunt with said series circuit for opening said switch to disconnect said source of potential when the 40 thermit action has occurred.

6. A combination in accordance with claim 5 in which said relay is provided with a retarding device.

In witness whereof, I hereunto subscribe 50 my name this 12th day of November, 1930.
WERNER ESPE.
